SPRING-STRUCTURE

Solomon Karpen, Chicago, Ill., assignor to S.
Karpen & Bros., Chicago, Ill., a corporation of
West Virginia

Application August 29, 1934, Serial No. 741,965

4 Claims. (Cl. 5—269)

This invention relates particularly to spring-structures adapted for use for various purposes, as for use in mattresses, bed-springs or for upholstery purposes.

5 An object of the invention is to provide improved spring-structure which will permit great flexibility while at the same time substantially avoiding noise, caused by the clashing of the end-rings against each other. A further object is to 10 provide a spring-structure which may be rolled without producing distortion or bending of the end-rings and their connections.

The invention is illustrated in a preferred embodiment in the accompanying drawing, in 15 which—

Figure 1 is a plan view of spring-structure embodying my invention; Fig. 2, a plan view of a modified form of spring-structure; Fig. 3, a sectional detail view, the section being taken as indicated at line 3 of Fig. 1; Fig. 4, a plan detail view of a modified form of spring structure embodying my invention; Fig. 5, a sectional view, the section being taken as indicated at line 5 of Fig. 4; and Fig. 6, an enlarged view of the structure shown in Fig. 4, the view being taken as indicated at line 6 of Fig. 4.

Referring to Fig. 1 and Fig. 3, the spring-structure shown comprises coil springs A, A, A, and helical connectors B, B connecting the springs.

30 The springs A may, if desired, be of the hour-glass type of upholstery springs, in which event helical connectors will ordinarily be employed to connect the end-rings at both sides of the spring structure.

35 It has been common practice to provide such end-rings with depressions which extend below the end-rings in a vertical plane and such depressed portions have been connected by helical connectors. Such structure has the disadvantage 40 of producing shoulders lying against the end-rings which tend to engage the end-rings when the mattress is rolled or flexed. This produces a clashing of the shoulders against the end-rings, resulting in noise and in distortion of the de- 45 pressions and the end-rings.

The characterizing feature of the present invention is that the depressions, instead of extending in a vertical plane below the end-rings, are slanted laterally at suitable angles so that the 50 end-rings are spaced sufficiently apart to permit flexing of the coil springs without causing the shoulders of the depressions to engage the end-rings.

In the construction shown in Figs. 1 and 3, the 55 end-rings 10 of coil springs A are provided with

depressions 11 which extend laterally and downwardly. The bottom rounds 12 of the depressions, as shown more clearly in Fig. 3, are brought substantially in contact. In the illustration shown in Fig. 3, the angle of movement between 5 the walls of the depression above the rounds 12 is almost 90°, thus permitting wide relative movement of the adjacent coil springs without any contact other than that between the adjacent rounds 12, 12. If desired, the angle of inclina- 10 tion away from the vertical may be increased or it may be decreased. I prefer, however, to have the depressions extending sufficiently below the plane of the end-rings to permit the connector B to lie below such plane. This construction main- 15 tains the helical connectors out of contact with the fabric, etc., enclosing the spring structure while at the same time permitting great flexibility of the structure.

In the spring structure shown in Fig. 2, the 20 springs A', A', A' are connected by helical connectors B'. In this structure, however, I avoid the knots 13 which are employed in the construction shown in Fig. 1. It will be noted that each of the springs A' is provided with at least one 25 depression 14 which terminates in a free end 15. Each of the free end depressions is engaged by a helical connector B' so as to secure it to the adjacent depression of the adjacent coil spring A'. The free end depressions 14, as well as the de- 30 pressions 16, which do not terminate in a free end, are slanted outwardly and downwardly in the same manner as the depressions 11 of the coil spring A.

It will be noted that the free end depressions 35 14 are each provided with a shoulder 17, a shank 18 and a shoulder 19 adjacent the end 15. The shoulder 17 is firmly engaged by the helical connector B' and is sufficiently strong to maintain the depression firmly in contact with the adjacent 40 depression when engaged by the helical connector. If desired, therefore, the shoulder 19 may be cut away, leaving only the shoulder 17 and the shank 18. With the structure shown in Fig. 2, increased flexibility over that shown in Fig. 1 45 is produced by the free end depressions 14; at the same time, the knotting operation is eliminated.

In the spring construction shown in Figs. 4, 5, and 6, the adjacent end-rings 20 of the spring 50 structure, such as is illustrated in Fig. 2, are provided with depressions 21 which extend below the end-rings in a substantially vertical plane, as illustrated more clearly in Fig. 5, the depressions being connected by a helical connector B². One of 55

the depressions is, however, provided with a free end 22, the shoulder 23 of the last-mentioned depression being engaged by coils of the connector B² and serving to lock the depression firmly 5 against the adjacent depression. It will be noted that the free end 22 does not extend above the connector B². However, if desired, the end may be so extended in accordance with the showing in Fig. 2.

10 In each construction described, it will be observed that increased flexibility is afforded, while at the same time the helical connector is supported below the plane of the end-ring. The free end depression shown in Figs. 4, 5, and 6 brings 15 about increased flexibility by eliminating one of the shoulders, while in the construction shown in Figs. 1 and 2, increased flexibility is afforded by angularly related depressions. The structures shown in Figs. 2, 4, 5, and 6 have the further advantage over the structure shown in Fig. 1, in 20 that the knotted ends 13 are eliminated.

The foregoing detailed description is given for clearness of understanding only, and no unnecessary limitations should be understood therefrom, but the appended claims should be construed as broadly as permissible, in view of the prior art.

What I claim as new, and desire to secure by Letters Patent, is:

30 1. A spring-structure comprising parallel rows of upholstery springs having end-rings disposed in adjacent relation at lines between said rows, each of said end-rings where adjacent to one on the opposite side of the row having an outwardly 35 and downwardly extending depression, and helical connections arranged between said rows and

having threaded engagement with said depressions and holding the bottom portions of such adjacent depressions substantially in contact.

2. A spring-structure comprising parallel rows 5 of upholstery springs having end-rings disposed in horizontal alignment but slightly spaced apart, each of said end-rings where adjacent to one on the opposite side of the row having a downwardly and laterally extending depression, and helical connections arranged between said rows below the 10 plane of the end-rings and having threaded engagement with said depressions and holding the bottom portions of said adjacent depressions substantially in contact.

3. A spring-structure comprising parallel rows 15 of upholstery springs having end-rings juxtaposed but slightly spaced apart, each of said end-rings where adjacent to one on the opposite side of the row having a depression slanting downwardly and outwardly, some of said depressions terminating 20 in free ends, and helical connections arranged between said rows and having threaded engagement with said depressions and holding the bottom portions of such adjacent depressions substantially in contact.

25 4. A spring structure comprising adjacent rows 30 of upholstery springs having end-rings juxtaposed but slightly spaced apart, each of said end-rings where adjacent to one on the opposite side of the row having a laterally extending depression below the plane of the end-rings, and helical connections arranged between said rows and having threaded engagement with said depressions and holding the bottom portions of such adjacent depressions substantially in contact.

35 SOLOMON KARPEN.
